GAME DEVICE

Joseph D. Irwin, Portsmouth, Va., assignor of one-half to Jordan W. Grant, Portsmouth, Va.

Application August 11, 1938, Serial No. 224,396

2 Claims. (Cl. 273—98)

This invention relates to a game device and it consists in the constructions, arrangements and combinations herein described and claimed.

It is an object of the invention to provide a game device in which a tethered ball is involved, as well as receiver cups into which the ball is to be selectively deposited upon manipulation of a support handle or the like.

It is a further object of the invention to provide a device of the character stated in which the receiver cups are longitudinally adjustable upon their supporting handle.

It is a still further object of the invention to provide a game device of the character stated which is simple of construction and amusing as well as requiring skill for the accomplishment of the ends sought.

Additional objects, advantages and features of invention will be apparent from the following description considered in conjunction with the accompanying drawing, wherein

Figure 1 is a fragmentary longitudinal sectional view of one embodiment of the invention.

Figure 2 is a fragmentary top plan view of one end thereof.

Figure 3 is a cross section on the line 3—3 of Fig. 2.

Figure 4 is a cross section illustrating a modified form of receiver mounting.

Figure 5 is a side elevation thereof.

Figure 6 is a longitudinal sectional view of a further modification of the receiver mounting.

Figure 7 is a cross section on the line 7—7 of Figure 6.

Figure 8 is a detail side elevational view of the receiver retaining means.

Attention is first invited to Figure 1 wherein there is shown a support member 10 which may be of any suitable shape and length and upon one end of which there is fixed a hand grip 11, whereby the rod may be actuated in a manner presently to be described.

The number 10 in the present instance is shown as a flat and rectangular bar, as seen in top plan, and has a pair of longitudinally extended slots 12 and 13 separated by a solid portion 14 positioned preferably intermediate the length of the slots.

The portion 14 of the rod has an aperture 15 formed therethrough for anchorage of a strand, cord, or the like, 16, the free end of the strand having secured thereto a ball 17. The strand 16 will be of a length so as to readily permit the ball to seat within respective receiver cups, as will be described.

A receiver cup 18 is slidably mounted in the slot 12, and a similar cup 19 is mounted in the slot 13 and since the construction of the cups 18—19 are identical, a description of one will suffice for a clear understanding of the device. 5

The receiver cup 18 is of a semi-spherical shape, preferably, the open end being presented so as to seat the ball 17 freely, and from the base of the cup there is a screw stud 20 of a length projecting through the slot 12 for reception of a 10 thumb nut 21. Fixed to the stud 20 there is a retainer plate 22 comprising lugs 23 slidably disposed in the slot 12.

From the foregoing, it will be seen that the cups 18—19 may be adjusted to a desired position along 15 respective slots by merely loosening the thumb nut 21, and then tightening the nut after adjustment has been obtained.

In Figures 4 and 5 the rod 10 is shown as a channel bar, the slots 12' and 13' being formed 20 in the vertical walls thereof. In this instance, the stud 24 comprises a lateral lug 25 adapted for slidable movement in one of the slots, while the opposite side of the stud 24 projects through the other slot and receives a thumb nut 26. Tightening or loosening of the nut 26 obviously permits longitudinal adjustment of the receiver cup.

In Figures 6, 7 and 8 a further modification of the device is shown and in this form the rod is illustrated as a rectangular tubular sleeve, one 30 wall of which is provided with a plurality of longitudinally spaced aperture 27. The cup in this instance has a rectangular tubular sleeve 28 of a size freely slidable upon the rod, and further has a leaf spring 29 fixed thereto. The free end of 35 the spring 29 has a pin 30 for registry with respective apertures 27 for securing of the receiver cup upon the rod.

In use, the device is grasped by the handle 11 and given an up and down swinging motion, imparting movement to the ball 17. At the time the ball is in the air, the operator directs the device in a manner to catch the ball in one of the cups. Obviously, this will require practice and considerable skill, as well as a quick eye, but after 45 a time it will be found to be quite easy, and in order that an expert may still find amusement, the positioning of the cups may be varied, presenting an entirely different gauge of distance, etc. Or, one of the cups may be placed closer to 50 the anchorage of the ball, and thus arranged, the problem of catching the ball in the cups will require a still different manipulation of the device for each cup.

While I have shown and described preferred 55

constructions, this is by way of illustration only, and I consider as my own all such modifications as fairly fall within the scope of the appended claims.

5 I claim:

1. In a device of the class described, an elongated support member having a pair of oppositely disposed longitudinal slots, a receiver-cup associated with each slot, said cup members each having a threaded stem extended through respective slots, a retainer plate on each cup, said plate having lugs for sliding engagement in respective slots, a nut on the threaded stem for engaging the underside of the support member, a

strand member anchored to the support member intermediate of the slots, and a ball member secured to the free end of the strand complementary to respective cups.

2. In a device of the character described, a support member having a pair of slots, a receiver cup associated with each slot, said cup members each having a stem extended through respective slots, means on the stems for clamping the cups in an adjusted position of movement along the 10 slots, a strand member anchored to the support member intermediate of the slots, and a ball member secured to the free end of the strand.

JOSEPH D. IRWIN.
